CRATE

Henry A. Keiner, Richmond Hill, N. Y., assignor
to Keiner Williams Stamping Co., Richmond
Hill, N. Y., a corporation of New York

Application December 30, 1933, Serial No. 704,629

5 Claims. (Cl. 217—19)

This invention relates to crates, especially milk bottle crates, and it has for its object to provide a strong and substantial crate which can be repaired easily and at comparatively low cost when 5 damaged in the manner in which crates of this kind are generally damaged in commercial use.

Bottle crates are usually made with the sides and ends composed of a plurality of boards, the joints between the boards of the sides being 10 matched or staggered with respect to the joints between the boards of the ends. These crates are provided with means for supporting and separating the bottles and these means may be of many different kinds. It has been customary heretofore to reinforce and protect the corners of the 15 crates with outside and inside angle members and with stacking members, and these members are made and arranged in many different ways. The top board of each end is provided with a cut-out 20 to form a handle which considerably reduces the strength of these top boards.

The crates are quite heavy when filled and they are handled more or less roughly and are subjected to considerable strain and abuse. Sometimes they are dragged along by the use of hooks 25 engaged with the top end boards of the crate, or with the top side boards, and sometimes the crates are carried on conveyors which engage one or more of the bottom boards during the washing, 30 filling and delivery operations.

These and other conditions to which the crates are subjected result in damage to the top and bottom boards requiring replacement of the damaged boards and this sometimes costs as much 35 in some crate structures as the production of a new crate because it involves disassembling the damaged crate and then reassembling the crate with replacement boards and other parts.

It is the object of my invention to provide a 40 crate which is protected at the corners as much or substantially as much as it is protected in commercial crates and still enable the crate to be repaired by replacing damaged boards without the necessity of disassembling the entire crate or of 45 removing more than the particular board requiring replacement.

And a further object of the invention is to protect the boards at the top and bottom of the crate and at the corners thereof in a novel manner 50 which will permit the replacement of one top or bottom board without disturbing the other top or bottom boards.

I have illustrated the invention in a crate in the accompanying drawing which has been selected for this purpose only and is not to be con-

sidered as a limiting embodiment of the invention, and referring thereto

Fig. 1 is a perspective view of a crate embodying the invention and having one outside angle member broken away;

Fig. 2 is a fragmentary elevation of an upper corner of the crate with the outside angle member broken away;

Fig. 3 is a detail top view of one corner of the 10 crate;

Fig. 4 is a horizontal sectional view on the line 4—4 of Fig. 1;

Fig. 5 is a detail perspective view of one end of one top member of the crate, and illustrating also a bottom member in reversed position;

Figs. 6—9 are detail sectional views showing modified forms of the invention; and

Fig. 10 is an elevation of a top end member partly broken away and in section illustrating another form of the invention.

Referring to the drawing, the crate comprises top end boards 10, top side boards 11 and corresponding bottom boards. The bottom boards are made and protected, preferably, in the same manner as the top boards of the crate and need not 25 be separately described. The top end boards 10 are cut out at 10' to provide handles or hand holes for the crate.

Outside angle members 12 and inside angle members 13 of suitable construction are fastened 30 to the crate at the corners thereof by rivets 14 or other suitable devices. In the form of crate illustrated these angle members extend substantially from the top to the bottom of the crate and stacking members 15 are fastened to the inside 35 angle members at the top thereof. Protective angle strips 16, preferably made of band iron, are secured to the top corners of the top boards, and similarly to the bottom corners of the bottom boards, by drive screws 17 extending through the 40 horizontal exposed parts of the protective strips into the outer exposed top edges of the boards. The upright parts of the protective angle strips on the end boards abut the side boards of the 45 crate and the upright parts of the protective angle strips on the side boards of the crate abut the outside angle members 12 and therefore the upright parts of the protective angle strips will be substantially concealed and always held in place 50 so that they need not be fastened, but they may be fastened to the ends of the boards by nails 18. For the reasons stated the nails may be omitted if desired and other fastening means may be substituted for the drive screws 17. The boards 55

are preferably recessed at 19, Figs. 5, 9, to accommodate the protective angle strips.

In Fig. 6, the free end of the upright member of the protective angle strip is inturned and engaged with a slot in the board as indicated at 20, Fig. 6, to assist in retaining the protective angle strip in place; and in Fig. 7 both ends 21 and 22 of the protective strip are engaged in slots in the board to retain the strip thereon; but in both cases I prefer to employ the fastening screws or some other fastening device. In Fig. 8, the protective strip 23 encloses the entire end of the board and is fastened in place by a drive screw 17 and a nail 18, or other fastening means. The ends 15 24 of the strip 23 are preferably inturned and engaged with slots in the opposing edges of the board. In Figs. 1-8, the protective strip extends along the edge of the top or bottom board and along the end thereof, but in Fig. 9 the protective strip 20 25 extends transversely over the edge and along the sides of the board at the end thereof and is fastened by rivet 25'. In Fig. 10, the protective strip extends along both ends, the top edge and partly along the bottom edge of the board and 25 is secured in place by drive screws 26 and nails 27, or other fastening means.

The invention provides a simple, strong, easily applied and substantial protection and reenforcement for the top and bottom boards at the 30 corners of the crate. These strips protect the boards at the corners of the crate against wear and they also reenforce the boards at the corners of the crate against splitting. If a top or bottom board is damaged and requires replacement it is 35 only necessary to knock out the rivets or other devices fastening the outside and inside angle members and the stacking members to that particular board and replace the board and the fastening devices. This does not involve any other 40 disassembling of the crate nor any skewing or displacement of any of the other boards of the crate, and it may be made in comparatively little time and at low cost. The top and bottom boards are the boards which most generally are 45 damaged and require replacement, as hereinbefore stated, but sometimes inside boards are damaged and require replacement and in that case it will be necessary to remove the top or bottom boards as well as the damaged inside board 50 to repair the crate. This, however, does not require any other disassembling of the crate than is indicated and the only real difficulty involved is removing the necessary rivets or other fastening devices which is a difficulty easily overcome by 55 those familiar with this class of work. The protective angle strips are preferably applied to the top and bottom side and end boards but this may be varied as conditions permit or require. The fact that these strips are fastened to the boards 60 and not to the angle members or the stacking members, and the further fact that the boards are not otherwise united except through the outside and inside members and stacking members and their fastening devices, facilitates the repair 65 and replacement of the top and bottom boards because very little mechanical work is required to accomplish this replacement and the protective strips on a damaged board may be used on other boards or other boards may be already provided 70 with protective strips to permit a quick replacement of damaged boards. In the form of the invention illustrated in the drawing it would only be necessary to remove two rivets from the rear end top board to replace that board, and this is 75 true also of the other top and bottom boards.

I have shown the invention in simple embodiments in the accompanying drawing but I do not mean thereby to restrict the adaptation of the invention to these particular embodiments; on the contrary I realize that there are many different kinds and constructions of crates for milk bottles and other bottles and I reserve the right to embody my invention in any crates for which it is or may be adapted and to make such changes therein as may be necessary or desirable for this or 10 other purposes within the scope of the following claims:

1. A crate having a corner formed by two adjacent boards, and means securing the boards together, the end of one board abutting the end 15 portion of the second board, at least one of said boards having an angle strip applied to the outer corner thereof, said angle strip being of a width substantially equal to the thickness of said board, said board having the end and outer edge thereof 20 recessed to receive said angle strip whereby the respective parts of said angle strip are flush with the outer edge and end of the board, and means securing said angle strip to said board.

2. A crate having a corner formed by two adjacent boards, and means securing the boards together, the end of one of the boards abutting a side of the second board, at least one of said boards having an angle strip applied to the outer corner thereof, said angle strip comprising a 30 length of strap metal bent to provide parts extending substantially at a right angle to each other, one flat part of the angle strip being confined to and abutting the exposed outer edge of the board and the other flat part of said angle strip extending over and being confined to the adjacent end of the board, and means holding said strip in place on the board.

3. A crate having a corner formed by two adjacent boards, and means securing the boards 40 together, the end of one of the boards abutting the end portion of the second board, at least one of said boards having an angle strip applied to the outer corner thereof, one flat part of the angle strip being confined to and abutting the 45 exposed outer edge of the board and the other flat part of said angle strip extending over and being confined to the adjacent end of the board, said board having the end and outer edge thereof recessed to receive said angle strip whereby the 50 respective parts of said angle strip are flush with the outer edge and end of the board, said board having a slot therein extending transversely of one of said edges at the end of the recess in said edge, an inturned end on the part of said strip mounted in said recess, said inturned end being disposed in said slot, and means securing said strip to said board.

4. A crate having a corner formed by two adjacent boards, the end of one of the boards abutting a side of the second board, an outside angle member, an inside angle member, means passing through said outside angle member, said boards and said inside angle member to secure said boards to said angle members, at least one of said boards having an angle strip applied to the outer corner thereof, said angle strip comprising a length of strap metal bent to provide parts extending substantially at a right angle to each other, one flat part of the angle strip being confined to and abutting the exposed outer edge of the board and the other flat part of said angle strip extending over and being confined to the adjacent end of the board, and means holding said 70 75 80 85 90 95

strip in place on said board, the means securing said boards to said outside and inside angle members being displaceable to permit replacement of said boards when required.

5. A crate having a corner formed by two adjacent boards, and means securing the boards together, the end of one of the boards abutting a

side of the other board, an upper corner of at least one of said boards being recessed in surfaces normal to each other, an angle strip comprising a length of strap metal having angularly extending parts seated in said recesses, and means holding said strip in place on the board.
